UNITED STATES PATENT OFFICE

2,187,825

MANUFACTURE OF SHOE HEELS

Thomas Baggott Clarke, Leicester, England, assignor to United Shoe Machinery Corporation, Borough of Flemington, N. J., a corporation of New Jersey

Application October 12, 1938, Serial No. 234,662
In Great Britain November 2, 1937

6 Claims. (Cl. 12—147)

This invention relates to the manufacture of shoe heels, particularly heels of the kind which are composed of a plurality of lifts assembled in a pile and secured together by one or more fasteners, such as heel building nails.

In the manufacture of women's high heels of this kind, the heel building nails, which must be long enough to reach through the entire pile of lifts and clinch, are often $2\frac{1}{4}$ inches or more in length and considerable difficulty occurs when driving ordinary, headed, heel building nails of such lengths in a heel building machine by reason of the erratic running of the nails in the pile of lifts while they are being driven. The greater the height of the heel, the longer the nails that must be used, and the longer the nails, the more probable it is that such trouble will occur. If the nails run in an unduly erratic manner while being driven, their paths being to some extent random and not under control, various troubles may occur, including insecure holding together of the lifts at parts of the heel, danger that nails later driven to attach the heel to a shoe may foul with improperly placed heel building nails, and danger that in extreme cases a heel building nail may run so far astray as to emerge from the side face of the heel or come sufficiently close to the side face to interfere with the subsequent trimming of the heel.

A large part of the reason for the above-mentioned difficulties is that, when using headed nails, the passages in the nail block of the heel building machine must be large enough to accommodate the nail heads and, therefore, considerably larger than the shank portions of the nails. Consequently, a considerable amount of play is permitted between each nail passage and the shank of the nail in said passage, with the result that there is no accurate control over the direction in which the nail is started into the heel and it is this lack of precise control by the nail guiding passages on the nails that appears responsible, as least in considerable measure, for the nails running in an erratic manner in a pile of lifts into which they are driven.

It is the object of the present invention to provide a method of making heels wherein the troubles referred to may be eliminated or greatly reduced. In the accomplishment of this object, I have provided a novel method of making a heel which includes driving a headless nail into a pile of lifts, the nail being driven from a drive passage which closely embraces it so that the direction of driving is accurately controlled and erratic running prevented or minimized, and then, for

example, compressing the heel between dies, the nail being such and being so driven that when the heel is compressed both ends of the nail are upset by being clinched or spread against the compressing die surfaces, to hold the lifts firmly together.

The above and other objects and features of the invention will be clear from the following description, read with reference to the accompanying drawing, of an illustrative procedure in accordance with the invention and of two forms of nails which may be employed in practicing the said procedure.

In the drawing,

Fig. 1 shows, prior to compression, a heel built up from superposed lifts held in assembled relation by three nails driven therein from the tread end of the heel and by one short nail driven therein from the attaching face end;

Fig. 2 shows more clearly the form of one of the nails seen in Fig. 1;

Fig. 3 shows the heel of Fig. 1 after compression;

Fig. 4 shows on a larger scale than Fig. 1 part of the heel shown in Fig. 1;

Fig. 5 shows on a larger scale than Fig. 3 part of the heel shown in Fig. 3;

Fig. 6 shows the manner in which the three nails are driven in building the heel shown in Fig. 1;

Fig. 7 shows on a larger scale than Fig. 6 certain parts shown in Fig. 6;

Fig. 8 shows the form of another nail which may be used in practicing the invention;

Fig. 9 shows a plate which it may be found advantageous to use in compressing the heel shown in Fig. 1; and

Fig. 10 shows the heel of Fig. 1 being compressed.

The invention will be described in connection with the manufacture of a comparatively high heel for a woman's shoe, namely a heel built up from fifteen lifts L, of which the majority are leatherboard, the lower two or three lifts being of leather. This heel when attached to a shoe will be about two inches high at its breast. In carrying out the illustrative procedure use is made of a heel building machine, parts of which are shown in Figs. 6 and 7 and which is constructed and arranged in much the same manner as the machine described in United States Letters Patent No. 2,046,443, granted July 7, 1936 upon an application filed in the names of W. R. Barclay et al. This heel building machine has a mold corresponding to the mold designated

- by the reference character 40 in the said patent and a nail block 15 corresponding to that shown at 10 in the patent, from any or all of three passages 16 in which one or more nails 5 may be driven upward by drivers 17 corresponding to the drivers shown at 18 in the said patent.
- The fifteen lifts L are first assembled in a pile in the mold 11 and then the machine is set in operation, whereupon the nails 13 are driven into 10 the pile of lifts from the tread end thereof and a short nail 19 is driven into the pile at the attaching face end by means corresponding to that of the machine described in the Barclay et al. patent.
- 15 The three nails 13 (of which but two are shown in Fig. 1) are of appropriate length and thickness for the heel being built, each nail being cylindrical for the most part and having a smooth shank 21. Each nail 13 has a pointed end 20 terminating a tapering portion 23 about one-eighth inch in length and at its head end, instead of a head, each nail has a recess 25. The recess 25 is conical in shape, as shown in Figs. 2, 4 and 7, and constitutes the whole end surface of the nail. Since the nails 13 have no heads they can readily be driven through passages only slightly larger in diameter than the shanks 21. For example, the passages 16 in the nail block 15 may be about .116 inch in diameter when nails having a diameter of .104 inch are to be driven. I have found that passages of this size serve to embrace the nails sufficiently closely during driving to insure that the paths of the nails will be controlled within much closer limits than has hitherto been the case when headed nails have been driven in similar fashion. The amount of clearance, .006 inch, between the nails 13 and the passages 16 is not enough to 30 allow any substantial degree of erratic running but is enough to allow the nails readily to be inserted in the passages 16 even though, as sometimes happens, the nails may have very small projecting fins around the recesses 25 resulting from the manner in which the nails have been 35 manufactured.
- The nail drivers 17 have conical tips, as shown at 27, which cooperate with the recesses 25 in the nails during the driving operation in the manner illustrated in Fig. 7 and the extent of 40 movement of the drivers is such that the nails are not driven flush with the surface of the tread end of the heel but are left projecting a short distance therefrom, as shown in Figs. 1 and 4.
- 45 After the nails 13 have been so driven by the heel building machine, the heel is transferred to a compressing machine, parts of which are shown in Fig. 10. This machine is constructed and arranged in much the same manner as the machine described in United States Letters Patent No. 776,875, granted December 6, 1904, upon an application filed in the name of Eliphilet A. Tripp, and the heel is subjected therein to a compressing operation. As compressing pressure 50 is applied, the nails 13 are clinched over at their pointed ends upon the attaching face end of the heel by the heel seat die 31 of the compressing machine. At the same time, however, the other ends of the nails 13 are forced against a flat top- 55 lift plate 33 of the compressing machine and the effect of the pressure is such as to cause these ends of the nails to spread out laterally so that the recesses 25 disappear and heads 29 are formed (see Fig. 5), which heads may be about .128 inch 60 or more in diameter. Should the heel tend to

expand heightwise when the compressing pressure is released, it is found that the heads 29 thus formed upon the nails in most instances satisfactorily prevent the lower lift M adjacent to the heads 29 from forcing itself off the nails, the 5 nails securely holding the pile of lifts together.

Fig. 8 shows another form of nail 35 which may be used and which resembles the nail 13 in all respects except that it has a shank 37 which, instead of being smooth, has for the most part 10 a screw threaded exterior, as shown in Fig. 8. At one end the nail 35 has a recess 39 like the recess 25 and adjacent to this end the shank 37 has a short length of its exterior, as shown at 41, which is smooth and is not screw threaded, the 15 periphery of the recess 39 being thus smooth and continuous. Three nails 35 may in certain circumstances be advantageously employed alternatively to the three nails 13 in carrying out the procedure just described. When nails 35 are so 20 used the screw threaded exteriors of their shanks assist in holding the lifts L together against expansion after compression and thereby further reduce the danger of the lift M becoming loose. It is believed also that when nails 35 are so used, 25 a greater force being necessary to drive the nails through the lifts L, the compression is more effective to cause the formation of heads on the nails and less likely to cause the nails to pass through the lifts L without satisfactory formation 30 of the heads but with a greater degree of clinching at the attaching face end of the heel.

Fig. 9 shows a top-lift plate 43 which may be used alternatively to the plate 33 and which has three suitably spaced shallow circular recesses 45 35 in which the recessed ends of the nails 13 or 35 are accommodated at the beginning of the compression of the heel. As a result, at the finish of the compression, there is a short space between the heads formed on the nails and the 40 lift M, which allows the heel to expand slightly after compression without the lift M becoming loose.

While, for purposes of illustration, two specific forms of headless nails suitable for use in practicing the method of the present invention have been illustrated and described, it is apparent that headless nails of many other forms could be used as long as both ends of the nails are capable of being sufficiently clinched, spread or 50 otherwise upset by the pressure exerted upon them by the top-lift and heel seat dies of the heel compressing machine to insure that they will hold the heel lifts securely together under compression and not permit the endmost lifts of the 55 heel to become detached.

Having described the invention, what is claimed as new and desired to be secured by Letters Patent is:

1. The method of making a heel which comprises assembling a plurality of heel lifts into a pile, driving a headless nail into said pile, and then upsetting both ends of the nail, one upon the tread face end and the other upon the attaching face end of the heel. 60

2. The method of making a heel which comprises assembling a plurality of heel lifts into a pile, driving a headless nail into said pile, compressing the pile and, in the compressing operation, upsetting both ends of the nail, one upon 70 the tread face end and the other upon the attaching face end of the heel.

3. The method of making a heel which comprises assembling a plurality of heel lifts into a pile, driving a headless nail into said pile, com- 75

pressing the pile and, in the compressing operation, clinching one end of the nail upon one end face of the heel and spreading the other end of the nail upon the other end face of the heel.

5. 4. The method of making a heel which comprises assembling a plurality of heel lifts into a pile, driving a headless nail into said pile, and then applying pressure to spread the head end of the nail upon one end face of the heel and thereby form a head upon the nail.

10. 5. The method of making a heel which comprises assembling a plurality of heel lifts into a pile, driving a headless, pointed nail into the tread end of the pile, compressing the pile and,

in the compressing operation, clinching the point end of the nail upon the attaching face end of the heel and spreading the other end of the nail to form a head upon the tread face end of the heel.

5. 6. The method of making a heel which comprises assembling a plurality of heel lifts into a pile, driving a headless nail for such a distance into the pile as to leave its head end projecting a short distance therefrom, compressing the pile and, in the compressing operation, upsetting and forming a head upon the projecting head end of the nail.

THOMAS BAGGOTT CLARKE.
